UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,320,055.

Specification of Letters Patent. Patented Oct. 28, 1919.

Application filed March 28, 1917. Serial No. 157,918.

To all whom it may concern:

Be it known that I, RUDOLF E. HELLMUND, a subject of the Emperor of Germany, and a resident of Swissvale, in the 5 county of Allegheny and State of Pennsylvania, have invented a new and useful Improvement in Systems of Control, of which the following is a specification.

My invention relates to systems of control 10 and especially to the control of electric railway motors and the like during regenerative braking periods.

In order to brake a momentum-driven vehicle down a grade, with a maximum degree 15 of safety, it is desirable to impart a rather "flat" speed-torque curve to the regenerating machines, that is, a slight increase in speed of the vehicle should be accompanied by a relatively great increase of torque or 20 braking effort, whereby the vehicle will be prevented from running away. However, inasmuch as such "flat" operating characteristic may be accompanied by relatively heavy currents and sudden variations there- 25 of that render the machines liable to "flash-over" difficulties by reason of field-flux distortion and high voltage between commutator segments, some special relay devices or other arrangements should be provided to 30 counteract such sudden current changes, or a compromise should be effected between the above-mentioned "flat" operating characteristic and the opposite type of curve, namely, a relatively "steep" characteristic whereby 35 relatively great variations of current with speed are inherently prevented. Furthermore, in circumstances where the momentum-driven machine is operated in accordance with a "flat" curve, other arrangements 40 should be provided to insure an even distribution of load between the several machines.

One object of my present invention is to 45 provide a system of the above-indicated character, wherein a predetermined compounding effect is imparted to the machines individually, and a different type and degree of compounding effect is imparted to the machines jointly.

More specifically stated, it is an object of 50 my invention to provide an exciter system for momentum-driven main dynamo-electric machines embodying means for imparting a negative compounding effect to the ma-

chines individually and a lesser positive 55 compounding effect to the machines jointly; that is, the individual machines tend to operate in accordance with a relatively "steep" characteristic curve, whereas the joint or combined operation of the machines is rep- 60 resented by a relatively "flat" curve.

My invention may best be understood by reference to the accompanying drawings, disclosing various systems embodying the principles of my present invention to a 65 greater or less degree, and wherein Figure 1 is a diagrammatic view of a set of main circuits and auxiliary-machine circuits embodying my invention, together with certain governing circuits for the machines; Fig. 2 70 is a similar view of a modified system corresponding to Fig. 1; Fig. 3 is a diagrammatic view of an auxiliary governing system to be employed in connection with Fig. 2; and Fig. 4 to Fig. 11, inclusive, are sim- 75 plified diagrammatic views of main-machine circuits and auxiliary-machine circuits constituting modifications of the present invention.

Referring to Fig. 1, the system shown 80 comprises supply-circuit conductors, respectively marked "Trolley" and "Ground;" a plurality of main dynamo-electric machines respectively having armatures A1 and A2 and field windings F1 and F2 of the series 85 type; main-circuit stabilizing resistors R1 and R2 that are associated with the respective machines in a manner to be described; an auxiliary motor-generator set 1 that is driven from the supply circuit and is connected to excite the main field windings 90 during the regenerative period; a relay device 2 of the motor type for governing a controller 3 that is adapted to vary certain circuit connections of the motor-generator 95 set 1 and the relay 2 through the agency of an operating mechanism 4; and a master controller MC1 that is adapted to occupy a plurality of operative positions *a*, *b* and *c* for primarily controlling the operation of the 100 system.

The motor-generator set 1 comprises a driving or auxiliary motor armature 10 that is mechanically connected with an exciting or auxiliary generator armature 11 by 105 means of a shaft 12, or otherwise; a series-related field winding 13 for the driving armature 10; a regenerated-current-excited

field winding 14 for the exciting armature 11 and a second variable field winding 15 therefor that is connected in series-circuit relation with the driving motor armature 5 and field winding.

The relay device 2 comprises an oscillatable armature 16 which may be variably energized from the supply circuit and upon the shaft 17 of which an auxiliary switching device or drum controller 18 is mounted to carry a contact member 19 that is adapted to bridge a plurality of stationary control fingers 20, 20b and 20c when the relay device occupies certain of its positions, 10 *a'*, *b'* and *c'*, corresponding to positions *a*, *b* and *c* of the master controller MC1. A suitable spring 21 or its equivalent, is provided to normally hold the relay device in the illustrated position, *b'*, in accordance 15 with a familiar practice. An exciting field winding 22 for the relay device is energized from a resistor 23 connected in the main-armature or regenerative circuit. The relay device 2 is thus responsive to variations 20 of regenerated current, while the operation thereof may also be adjusted through the actuation of the controller 3 to vary a resistor 25 by means of control fingers 26 connected to various points thereof and successively engaged by a contact segment 27 25 as the controller 3 moves through its successive positions. It will be understood, however, that the relay device 2 may be actuated in accordance with variations of 30 main-machine torque, if desired, by connecting its field winding 22 across a portion of one of the main-circuit resistors R1 and R2 which, as subsequently pointed out, carry the sum of the corresponding main-armature and main-field-winding currents, such 35 sum being approximately proportional to the product thereof over a certain range and, therefore, to the machine torque.

A torque-relay action may also be obtained by connecting the relay armature 16 across either main field winding, and employing the illustrated connections for the relay field winding 22.

In addition to the control fingers 26 and 50 contact segment 27 of the controller 3 that are associated with the auxiliary-circuit resistor 25, a second series of control fingers 28 may be connected to selected points of the field winding 15 for the exciting armature 11, and a contact segment 29 of suitable configuration is provided for successively engaging the control fingers 28 in the desired sequence.

The operating mechanism 4 for the controller 3 is of a familiar electrically-controlled, pneumatically-actuated type and comprises a pinion 30 which is rigidly secured to one end of the operating shaft 31 of the controller and is adapted to mesh with 65 a horizontally-movable rack member 32, the

opposite ends of which constitute pistons 33 and 34 that travel within suitable operating cylinders 35 and 36, respectively. A normally closed valve 37 is associated with the outer end of the cylinder 35, and a normally open valve 38 communicates with the outer end of the other cylinder, fluid pressure being admitted to the respective valves through pipes or passages 39 and 40 from any suitable source (not shown). The valve 75 70 75 80 85 90 95 100 105 110 115 120 125 130 37 is provided with an actuating coil "On" for opening the valve when the coil is energized, and the other valve 38 is provided with a similar actuating coil "Off" which, when energized, closes the valve and effects communication of the cylinder 36 with the atmosphere.

The mechanical operation of the operating device 4, without regard to the electrical connections effected thereby, may be set forth as follows: By reason of the normally open condition of the valve 38, the pistons 33 and 34 are biased to the position shown, and the controller 3 occupies its "off" position. By concurrently energizing the coils "On" and "Off", the normal fluid-pressure conditions in the mechanism are reversed, that is, fluid pressure is admitted to the cylinder 35 and is exhausted from the cylinder 36, whereby a movement 95 of the pistons toward the right ensues, accompanied by a corresponding movement of the controller 3 through its operative positions.

To arrest such movement at any time, it is merely necessary to deenergize the "off" coil, whereby fluid pressure conditions in the mechanism are balanced and a positive and reliable stoppage thereof is effected. To produce a return movement of the mechanism, the actuating coils are concurrently deenergized, whereby fluid-pressure conditions revert to the original state and the apparatus is returned to the illustrated position.

For the sake of simplicity and clearness, I have omitted from the drawing various main and auxiliary-circuit switches and have shown the master controller MC1 as governing only the actuating coils of the operating mechanism 4. It will be understood that regenerative operation may be inaugurated in any well-known manner, which need not be discussed here. Assuming, therefore, that the master controller MC1 has been moved to its final operative position *c*, a circuit is completed from the positive terminal of a battery B, or other suitable source of energy, through conductor 42, control fingers 43 and 44—which are bridged by contact segment 45 of the master controller—conductor 46, actuating coil "On", and conductors 47 and 48 to the opposite battery terminal. Another circuit is completed from the contact segment 45 of the 130

master controller through control finger 50, conductor 51, actuating coil "Off" and conductor 52 to negative conductor 48.

Since both actuating coils of the operating mechanism 4 are concurrently energized, movement of the controller 3 occurs in accordance with the previously-described operating principles. To manually arrest such movement, at any time, the master controller 10 may be moved backwardly to its intermediate position *b*, whereby the contact segment 45 becomes disengaged from the control finger 50 to thus deenergize the "off" coil and effect the stoppage of the 15 mechanism, as previously set forth.

The main regenerative circuit is completed from the trolley through conductor 55, where the circuit divides, one branch including conductor 56, main armature A1, 20 junction-point 57 and the main-circuit resistor R1 to junction-point 58, and the other branch including conductor 59, main armature A2, junction-point 60 and the main-circuit resistor R2 to junction-point 58, whence 25 a common circuit is continued through conductor 61, field winding 14 for the exciting armature 11 and conductors 62, 63 and 64 to the negative supply-circuit conductor "Ground."

30 The main field winding circuit is established from the positive terminal of the exciting armature 11 through conductors 67, 68 and 62, field winding 14 for the exciting armature 11, conductor 61 to junction-point 58, where the circuit divides, one branch including main-circuit resistor R1, main field winding F1 and conductor 69 to junction-point 70, and the other branch including 35 main-circuit resistor R2 and main field winding F2 to junction-point 70, whence a common circuit is completed through conductor 71 to the negative terminal of the exciting armature.

An auxiliary circuit is completed from the 40 positively energized conductor 59 through conductor 72, auxiliary motor armature 10 and field winding 13 thereof, conductor 73, control fingers 28 and contact segment 29 of the controller 3 and thence, through a certain portion of the field winding 15 for the 45 exciting armature 11 and conductor 68, to the negative conductor 63.

A further auxiliary circuit is established from the positively-energized conductor 56 50 through conductor 75, coöperating control fingers 26 and contact segment 27 which are associated with the resistor 25, conductor 76, the armature 16 of the relay device 2 and conductors 77 and 64 to "ground." Since 55 the armature of the relay device is energized through the circuit just traced, and the field winding 22 therefor is energized in accordance with the regenerated current, as previously mentioned, the relay device is operative to vary the governed circuit connections 60

in accordance with variations of main-armature or regenerated current.

The operation of the main-circuit resistors R1 and R2 for inherently imparting to the machines individually a relatively 70 "steep" or negative compound characteristic will now be described. Assuming an incipient increase of regenerated current in the main armature A1, for example, the correspondingly increased voltage drop across 75 the resistor R1 immediately effects a reduction of the voltage that is available for delivery from the exciting armature 11 to the main field winding F1, since the resistor R1 is also in circuit with the main field winding 80 F1 and the exciting armature 11. The converse action takes place in case of an incipient decrease of regenerated current. Thus, the resistors R1 and R2 tend to inherently maintain a substantially constant main-armature or regenerated current, by reason 85 of the fact that the main-field-winding current is automatically varied oppositely or negatively with respect to the main-armature current variations. As will be understood, 90 by suitable design and proportion of parts, the "steepness" of the operating characteristic imparted to the individual machines by the resistors R1 and R2 may be selected to best meet operating requirements. The 95 regenerative connections just described form no part of my present invention except in so far as they perform a certain necessary function in coöperation therewith, and are fully set forth and claimed in my co-pending application, Serial No. 44,443, filed Aug. 9, 1915, patented April 1, 1919, No. 1,298,706.

In opposition to the negative compound effect imparted to the main machines individually in the manner just set forth, a 105 counteracting or positive compound effect, preferably of a lesser degree, is imparted to the machines jointly by reason of the employment of the regenerated-current-excited field winding 14 for the exciting armature 11, where the delivered voltage thereof tends to increase or decrease with variations of regenerated current. Thus, by suitably designing the auxiliary field winding 14, the 110 positive compound effect thereof upon the 115 motors jointly may be selected to cause the machines to operate, as a unit, in accordance with a relatively "flat" operating characteristic of the type previously described.

The automatic control of the system by 120 the relay device 2 when the master controller MC1 occupies its neutral or holding position *b*, will now be described. In general, movement of the relay device to the one or the other of its outer positions, *a'* and *c'*, respectively effects a backward and a forward 125 movement of the controller 3.

There is danger of the occurrence of excessive regenerated currents, corresponding, for instance, to the slipping-point of the ve- 130

hicle wheels, when the machines are operating in accordance with such a "flat" curve, especially in case of a sudden material variation of supply-circuit voltage, which may also lead to "flash-over" difficulties. Under such heavy-current conditions, the increased torque of the relay armature 16, by reason of the increased energization of the corresponding field winding 22, overcomes the opposing action of the spring 21 and actuates the drum controller 18 into position *a'*, whereby the control fingers 20*b* and 20*c*, which are respectively connected to the conductors 46 and 51, are disengaged from the contact segment 19, thereby de-energizing both the "off" and the "on" coils, provided the master controller occupies its position *b*, to cause a backward movement of the controller 3, in accordance with previously-described principles, until conditions in the various machine circuits are adjusted to conform to the new supply-circuit conditions. In the present case, such backward movement will gradually decrease the effective ampere-turns of the field winding 15 for the exciting armature 11 and thus tend to produce a decrease of the main-armature or regenerated current.

The limiting or permissible values of regenerated current may depend somewhat upon the speed of the vehicle, since "flash-over" difficulties are more liable to occur for a given current under high-speed conditions and, consequently, the resistor 25 in circuit with the armature 16 of the relay device 2 is also varied by a backward movement of the controller 3 to gradually reduce the active circuit resistance of the resistor 25. Thus, for the initial operative positions of the controller 3, which correspond to high-speed regenerative operation, the setting of the relay device 2 is of a lower value than during subsequent main-machine operation; that is, the initial regenerative current is kept relatively low in value.

Under predetermined low-current conditions, the spring 21 overcomes the torque of the relay armature 16 to effect the actuation of the relay device to position *c'*, whereby the actuating coils "On" and "Off" are re-energized to produce "forward" movement of the controller 3. Thus, the regenerated current is maintained by the relay device 2 within predetermined limits.

Furthermore, when the above-mentioned "flat" speed-torque characteristic is utilized, there is a possibility that, upon a sudden increase of the track grade, the machines may begin to accelerate and consume relatively heavy motor currents, with consequent danger of "flash-over" conditions. Whenever such reversed-current action occurs, the relay device 2 is adapted to effect the actuation of the drum controller 18 to the position *c'*, whereby the actuating coils "On" and "Off" are both energized and for-

ward movement of the controller 3 ensues until conditions are again suitable to produce regenerative operation. Thus, the momentum-driven machines will always exert a braking effect, while the master controller occupies its braking positions, until the controller 3 has reached its final position, wherein the voltage of the exciting armature 11 attains its maximum value and a relatively high degree of saturation of the main field windings is obtained. Under such conditions, reversal of the main-machine current is not injurious and, therefore, no further protection of the system in this respect is necessary.

Since the compounding effect of the resistors R1 and R2 is practically instantaneous in its action, and the opposing effect of the auxiliary field winding 14 operates with a slight time element, the rise of regenerated current in any case will be sufficiently tardy to permit the regulating operation of the relay device 2 before dangerous currents are obtained.

Referring to Fig. 2, the system shown comprises the supply-circuit conductors and the main dynamo-electric machines, as set forth in connection with Fig. 1 and, in addition, an exciting motor-generator set 80; a plurality of motor-type relay devices 81 and 82 for maintaining the regenerated current within predetermined limits; a plurality of solenoid-type relay devices 83, 84 and 85 for governing the system operation under conditions of a sudden interruption of supply-circuit voltage; a controller 86 that is operated by the mechanism 4 for varying the active circuit values of the main-circuit resistors R1 and R2; and a master controller MC2 that is adapted to occupy a plurality of operative positions *a* to *e*, inclusive, for adjusting the operation of the motor-type relay devices 81 and 82.

The main circuit resistors R1 and R2 serve the same function as that set forth in connection with Fig. 1, and their negative compounding effect upon the motors individually is counterbalanced to the desired degree by designing the exciting armature 11 with a drooping voltage-current characteristic, that is, a rapid decrease of voltage is produced upon an increase of current, within a predetermined range. Such a result may be obtained by a shifting of the brushes 90 and 91 of the exciting armature 11 by means of a suitable actuating device 92 to such an extent and in such a direction as to suitably increase the armature reactive effect. The exciting machine is also preferably provided with a damper winding that is located in the polar faces of the machine, in accordance with a familiar practice, to render the voltage changes of the armature relatively slow or sluggish and thus provide an appreciable time element 130

in such changes to allow for relay operation, for instance. For the sake of simplicity and clearness, such damper winding is here conventionally shown by a short-circuited coil 93.

The motor-type relay device 81 is provided with an oscillatable armature 95, upon the shaft 96 of which a switching device or drum controller 97 is mounted to 10 carry a contact segment 98 that normally bridges a pair of control fingers 99 for a purpose to be described. A field winding 100, energized from a predetermined portion of the main-circuit resistor R1, is provided and, since the armature 95 is energized from the main-machine or regenerated voltage, the operation of the relay device 81 occurs in accordance with variations of main-machine torque, as previously 15 pointed out. An opposing spring 21 is provided for the purpose of normally biasing the relay device to the illustrated position.

The second motor-type relay device 82 comprises an armature 101 for actuating a drum controller 102, upon which is located a contact segment 103 to connect a pair of stationary contact members 104 under predetermined conditions. A field winding 105 for the relay device is connected in parallel relation with the field winding 100 for the other relay device 81. An opposing spring 21 is also provided.

The solenoid-type relay device 83 has its actuating coil connected in the regenerative circuit and the relay occupies the illustrated upper position under conditions of normal regenerative current flow.

The solenoid-type relay devices 84 and 85 are energized from the supply circuit when the relay device 83 drops to its lower position and have different voltage settings corresponding, for example, to the torque settings of the motor-type relay devices 81 and 82, for maintaining the generated voltage of the momentum-driven main machines within any desired limits, after an interruption of supply-circuit voltage when the relay devices 81 and 82 are rendered inoperative, and the generated voltage is thus maintained at a value suitable for recommencing regenerative operation as soon as the supply-circuit voltage is resumed.

Referring temporarily to the auxiliary governing circuits shown in Fig. 3, such circuits comprise the actuating coils "On" and "Off" and various auxiliary contact members of the relay devices 81 to 85, inclusive, together with a battery B, or other suitable source of energy, and a governing switch 120.

Assuming that a preliminary regenerative operation obtains, the switch 120 is closed to complete a circuit from one terminal of the battery B through conductor

121, switch 120, conductor 122, contact member 98—which is normally bridged by control fingers 99 of the high-current relay device 81—auxiliary contact members 123 of the relay device 83 in its upper or energized position, conductor 124, where the circuit divides, one branch including the actuating coil "On" and conductor 125 to junction-point 126, and the other branch including conductor 128, contact segment 75 103—which is normally bridged by control fingers 104 of the low-current relay device 82—the actuating coil "Off", and conductor 130 to junction-point 126, whence a common circuit is completed through conductor 131 to the negative battery terminal. 80

Under such conditions the controller 86 is actuated by its operating mechanism 4 into successive operative positions, the main circuits being established from the 85 trolley through the main armatures A1 and A2 in parallel relation to conductors 135 and 136, respectively, and thence through control fingers 110 and contact segment 111 which are associated with the main-circuit 90 resistor R1 and through control fingers 112 and contact segment 113 which are associated with the main-circuit resistor R2, circuit being continued from the respective resistors through conductors 137 and 138 to 95 conductor 139, the actuating coil of the relay device 83 and conductor 140 to the negative supply-circuit conductor Ground.

The circuits of the auxiliary exciting armature 11, the auxiliary motor armature 100 10 and their field windings are substantially the same as set forth in connection with Fig. 1 and need not be traced.

An auxiliary circuit is established from the trolley through conductor 142, control 105 fingers 143, which are successively engaged in a predetermined sequence by contact segment 144 of the master controller MC2 to vary a resistor 145, conductor 146, the armature 95 of the relay device 81, conductor 110 147, the armature 101 of the relay device 82 and conductor 148 to the negative conductor 139.

A further auxiliary circuit is completed from the trolley through conductors 150 and 115 151, the actuating coils of the relay devices 85 and 84 in series relation, stationary contact members 152, which are bridged by movable contact member 123 of the relay device 83, when occupying its lower or no-current position, and conductor 154 to ground.

Whenever the regenerated current decreases to a predetermined lower value, the low-current relay device 82 is biased by the 125 spring 21 to occupy the illustrated position to permit "forward" movement of the controller 86 by completing the energizing circuit of the "off" coil, as previously described, thereby gradually excluding the 130

resistors R1 and R2 from circuit. Under normal current conditions, the torque of the relay armature 101 opens the circuit in question, and the controller 86 is held stationary.

5 Upon the occurrence of a predetermined relatively heavy regenerated current, the torque of the relay device 81 is sufficiently increased to overcome the opposing action of the spring 21 and actuate the drum controller 97 into such position as to effect the disengagement of the contact segment 98 from the control fingers 99, thereby interrupting the common energizing circuit of the actuating coils "On" and "Off", as 10 clearly indicated in Fig. 3, to effect a return movement of the controller 86 and thus insert gradually increasing amounts of the resistors R1 and R2 in circuit to cause a reduction of the regenerated current. When 15 such reduction has taken place, the spring 21 again predominates to actuate the relay device into the illustrated position and permit forward operation of the controller 86.

Thus, by suitably adjusting the relay devices 81 and 82, which may be connected through individual master controllers and resistors, if desired, instead of the common master controller MC2 and resistor 145, the regenerated current may be automatically 20 maintained between predetermined current or torque limits to best meet operating requirements.

If, for any reason, for example, an interruption of supply-circuit voltage, the regenerated current should decrease to a relatively low value, the relay device 83 drops to its lower position to interrupt the combined energizing circuit of the actuating coils "On" and "Off" and to close the energizing circuit for the actuating coils of the relay devices 84 and 85 by the bridging of stationary contact members 152 by the movable contact member 123, and a new circuit is thereupon completed from the positively 35 energized conductor 122 (Fig. 3) through conductor 160, coöperating contact members 161 of the high-voltage relay device 84 in its lower or normal position, conductor 162, stationary contact terminals 163 which are 40 bridged by contact disk 164 of the no-current relay device 83 in its lower position, conductor 124, where the circuit divides, one branch including the actuating coil "On" and conductor 125 to junction-point 126, and the 45 other branch including conductors 128 and 165, stationary contact members 166 which are bridged by contact disk 167 of the no-current relay device 83 in its lower position, conductor 168, coöperating stationary and 50 movable contact members 169 of the low-voltage relay device 85 when occupying its lower position, conductor 170, actuating coil "Off" and conductor 130 to the junction-point 126, whence circuit is completed as 55 already traced.

The relay device 85 drops to its lower or closed position to effect an actuation of the controller 86 toward its final operating position whenever the main-machine generated voltage reaches a certain lower value, 70 while the high-voltage relay device 84 is lifted to its upper or open position to effect a backward movement of the controller whenever the generated voltage rises above a predetermined higher value. 75

Thus, the generated voltage of the main machines, under conditions of interruption of the regenerative circuit or supply-circuit connection, may be maintained between any predetermined limits, preferably slightly 80 above the supply-circuit voltage and, consequently, upon the resumption of supply-circuit voltage and the resultant lifting of the no-current relay device 83 to its illustrated upper position, the control of the 85 system is again invested in the motor-type relay devices 81 and 82, and the solenoid-type relay devices 84 and 85 are rendered inoperative, such transfer of governing connections being accompanied by no heavy- 90 current surges, by reason of the above-described regulation of generated voltage.

Referring to Fig. 4, the simplified system shown comprises the main dynamo-electric machine and the main-circuit resistors, 95 as illustrated in Fig. 1, as well as the auxiliary armatures 10 and 11 and, in addition, a series compensating field winding 175 for the auxiliary motor armature 10 and a shunt field winding 176 therefor, the excitation of 100 which may be varied by means of a resistor 177 in circuit therewith, and a plurality of field windings 181 and 182 for the exciting armature 11 that are respectively connected in series-circuit relation with the 105 main-circuit resistors R1 and R2.

The exciting armature 11 is thus provided with field fluxes corresponding to the sum of the individual regenerated and field-winding currents of the main dynamo-electric machines. In this way, the inductive and resistive effects of the auxiliary field windings 181 and 182 assist the above-described negative compounding effect of the resistors R1 and R2, and the positive compounding effect of the auxiliary field windings upon the exciting armature 11 relative to the negative effect produced upon the machines individually by the corresponding resistors and auxiliary field windings may be varied to meet any desired requirements, the negative effect preferably slightly predominating, for reasons previously explained. 115

Fig. 5 differs from Fig. 4 only in the 125 substitution of the field winding 14, which is energized by the combined main-armature or total regenerated current, for the field windings 181 and 182 of Fig. 4. The desired relative effects of negative and posi- 130

tive compounding may thus be secured in any desired proportion.

A desirable combination of circuits comprises the use of the low-current relay device 82 of Fig. 2, with its field winding 105 connected across the field winding 14 of Fig. 5. Such connection would render the action of the relay device very sensitive to changes of regenerated current, by reason of the corresponding inductive effect of the field winding 14.

In Fig. 6, the main dynamo-electric machines are provided with subdivided field windings F3 and F4 that are connected in circuit with the non-corresponding armatures A2 and A1, respectively, the remaining circuits being similar to those previously set forth.

Under conditions of regenerative operation, the main armature or regenerative circuit is established from the trolley where the circuit divides, one branch including conductor 200, main armature A1 conductor 201, a predetermined upper and reversely-connected section 202 of the non-corresponding field winding F4 and conductor 203 to the main-circuit resistor R2, and a second branch including conductor 204, main armature A2, conductor 205, a predetermined upper and reversed section 206 of the non-corresponding field winding F3 and conductor 207 to the main-circuit resistor R1. In the present instance, the resistors R1 and R2 are connected in parallel relation and may, therefore, be supplanted by a single equivalent resistor. A common circuit is completed from junction-point 208 of the resistors through conductor 209 to ground.

The main-circuit resistors R1 and R2 inherently impart the above-mentioned negative compounding characteristic to the series related main armatures individually and such compounding effect is counteracted to any desired degree by the proper provision of ampere-turns corresponding to the regenerated current flowing in a positive or aiding direction, with respect to main-armature voltage, as indicated by the arrows, through the reversed main-field-winding sections 202 and 206 which, consequently, act cumulatively with respect to the principal portions of the main field windings and the positive compounding effect thereof.

The final result may be predetermined by suitable arrangement of parts to produce the desired imparting of a relatively "flat" speed-torque curve to the main machines jointly. Furthermore, the interconnection of non-corresponding main armatures and field windings tends to automatically balance or distribute the load between the main machines since, for example, if the current traversing the main armature A1 increases, the increased flux emitted by re-

versed section 202 of the non-corresponding field winding F4 will cause an increase of voltage and, therefore, of current in the other or corresponding main armature A2.

In Fig. 7, a somewhat similar system is illustrated, wherein the circuit connections are simplified to a certain extent and, in particular, the system is better adapted for use with the well-known standard "field control" type of railway motors. In the present instance, the main armature A1 is connected to an intermediate tap-point 210 of the non-corresponding field winding F2, and the other main armature A2 is connected to an intermediate tap-point 211 of the non-corresponding field winding F1. A single resistor R3 in the common negative conductor leading to ground is substituted for the parallel-connected resistors R1 and R2 of Fig. 6.

As indicated by the various arrows, the effect of the two sections of each main field winding is cumulative and, therefore, the positive compounding action of the regenerated and exciting armature currents in the main field windings will counteract, to any desired degree, the negative compounding effect of the main-circuit resistor R3. Furthermore, the above-described load-balancing effect is again produced by the interconnection of non-corresponding main armatures and field windings. Moreover, if the design of parts is such that the upper or regenerated-current-excited sections 212 and 213 of the main field windings are adapted to produce the greater portion of the necessary excitation, the exciting current furnished to the other main-field-winding portions may be relatively small, with a resultant reduction in the initial cost and in the maintenance expense of the auxiliary motor-generator set.

Referring to Fig. 8, the main-field-winding circuits are established from one terminal of the exciting armature 11 through two similar parallel-connected circuits, one of which includes the main-circuit resistor R1, the main field winding F1 and a variable resistor R4, and the other of which includes main-circuit resistor R2, main field winding F2 and a variable resistor R5, common circuit being completed from the junction-point of the resistors R4 and R5 through a series-related field winding 183 for the exciting armature 11 to the negative terminal thereof.

The main-armature circuits are established from the trolley to a junction-point 214, where the circuit divides, one branch including a series-related field winding 178 for the auxiliary motor armature 10, the main armature A1 and the main resistor R1, and the other branch including a similar field winding 179 that is connected in series relation with the main armature A2 130

and the main resistor R2. The auxiliary motor armature 10 is also provided with the series-related field winding 13 which is differentially related to the regenerated-current-excited field windings 178 and 179.

- The above-mentioned negative compounding effect that is produced by the main-circuit resistors R1 and R2 is counteracted to any desired extent in the following manner:
- 10 Assuming an incipient increase of regenerated current in the main armature A1, for example, the corresponding increase of current traversing the field winding 178 for the auxiliary motor armature 10 causes a decrease of the total effective flux threading the armature, by reason of the differential relation of the field windings 178 and 13, whereby the motor-generator set speeds up to produce an increased voltage across the terminals of the exciting armature 11 to thus secure the desired imparting of a relatively "flat" speed-torque curve to the main machines jointly. It will be understood, without further description, that a corresponding action takes place through the agency of the auxiliary field winding 179 when the current traversing the main armature A2 increases and, in either case, a converse action occurs upon an incipient decrease of main-armature current.

  - 20
  - 25
  - 30

In Fig. 9, the main-circuit resistors R1 and R2 occupy the same respective positions relative to the main field windings F1 and F2, but the main armatures A1 and A2 are connected to the outer terminals of the non-corresponding resistors and, consequently, to the upper terminals of the non-corresponding main field windings, whereby the resistors R1 and R2 carry a current equal to the difference between the corresponding regenerated current and the main-field-winding or exciting current, as indicated by the arrows.

The main circuit is established from the trolley through two similar parallel circuits, one branch including conductor 220, main armature A1, conductor 221, main resistor R2, and junction-point 222, and the other branch including conductor 223, main armature A2, conductor 224, main resistor R1 and the junction-point 222, whence a common circuit is completed through conductor 225, the auxiliary exciting armature 11, conductor 226, field winding 185 for the exciting armature and conductor 227 to the negative supply-circuit conductor Ground.

In the present instance, the exciting armature 11 is also provided with a shunt-excited field winding 184 that is differential to the field winding 185, as indicated by the plus and minus signs, and the auxiliary motor armature 10 has a shunt-excited field winding 176.

By reason of the circuit connection just

traced, and as indicated by the various arrows, the resistors R1 and R2 exert a positive compounding effect rather than the negative compounding effect previously described, that is to say, any increase of regenerated current reduces the effective voltage drop, and the corresponding main-field-winding voltage is accordingly increased. The converse action occurs in case of an incipient decrease of main-armature current. However, the regenerated-current-excited field winding 185 for the exciting armature 11 is designed to produce a negative or opposing compounding effect upon the exciting armature, which effect is preferably slightly greater than the positive compounding effect produced by the main-circuit resistors. Thus, the final result is similar to that obtained by the use of the previously described systems, although the function of the main resistors and the exciting-armature field winding have been interchanged.

The system shown in Fig. 10 comprises the main dynamo-electric machines having the armatures A1 and A2 and sub-divided field windings F1 and F2 together with a common main-circuit resistor R3, and a motor-generator set having the series-compensating field winding 175, the shunt-excited field winding 176 for the auxiliary motor armature 10 and the supply-circuit-excited field winding 15 for the auxiliary generator armature 11. In the present instance, the resistor R3 and the upper portions 212 and 213 of the main field windings carry a current equal to the difference between the exciting current and the regenerated current, as indicated by the various arrows. As described in connection with Fig. 9, the resistor R3 produces a positive effect, while the upper field winding sections 212 and 213 cause a somewhat larger negative compounding effect.

Furthermore, the field winding portions 212 and 213 tend to maintain an even distribution of load between the main machines, since an increased current in the armature A1, for example, and, therefore, in the field winding section 212, causes a diminution of the effective field flux emitted by the corresponding field winding F2, whereby the current traversing the armature A1 is caused to subside and the other machine absorbs additional load corresponding to the reduction of load upon the armature A1.

In Fig. 11, the main armatures A1 and A2 are connected to the lower terminals of the non-corresponding field windings F2 and F1, while the common main-circuit resistor R3 is connected in the same position as that shown in Fig. 10. The variable resistors R4 and R5 are again connected to the lower terminals of the main field windings F1 and F2, respectively.

The auxiliary motor-generator set is shown as provided with the field windings 176 and 15 for the auxiliary-motor armature 10 and generator armature 11, respectively.

5 One main circuit is established from the trolley through conductor 230, main armature A1, conductor 231, which is connected to the lower terminal 232 of the field winding F2, and thence, through the main field winding F2 and conductor 233, to junction-point 234. A second main circuit is completed from the trolley through conductor 235, main armature A2, conductor 236, which is connected to the lower terminal 237 of the main field winding F1, whence circuit is continued through the field winding and conductor 238 to the junction-point 234, a common circuit being completed through the resistor R3 and conductors 239 and 240 to ground.

The main-field-winding circuit is completed from the positive terminal of the exciting armature 11, through conductor 241 and 239, and the main-circuit resistor R3 to junction-point 234, where the circuit divides, one branch including conductor 233, main field winding F2, conductor 242, variable resistor R5 and conductor 243 to junction-point 244, and the other branch including conductor 238, main field winding F1, conductor 245, variable resistor R4 and conductor 246 to the junction-point 244, whence circuit is completed through conductor 247 to the opposite terminal of the exciting armature 11.

Under conditions of regenerative operation, the main-armature or regenerated current traverses the resistor R3 and also traverses the main field windings, which produce a relatively strong positive compounding effect. However, the value of the resistor R3 is selected to produce a negative compounding action which slightly more than neutralizes the positive compounding effect of the field windings, whereby the desired regenerative regulating operation is secured. Furthermore, the cross-connection of the main armatures and field windings tends to secure an even distribution of regenerated current, in the manner previously described.

I do not wish to be restricted to the specific circuit connections or arrangement of parts herein set forth, as various modifications thereof may be effected without departing from the spirit and scope of my invention. I desire, therefore, that only such limitations shall be imposed as are indicated in the appended claims.

60 I claim as my invention:—

1. In a system of regenerative control, the combination with a plurality of momentum-driven dynamo-electric machines, of means for imparting a predetermined compound-

ing effect to the machines individually, and 65 other single means for imparting an opposing compounding effect to the machines jointly.

2. In a system of regenerative control, the combination with a plurality of momentum-driven dynamo-electric machines, of means for imparting a predetermined compounding effect of one type to the machines individually, and other single means for imparting a compounding effect of the opposite type and of a different degree to the machines jointly. 70 75

3. In a system of regenerative control, the combination with a plurality of momentum-driven dynamo-electric machines, of means 80 for imparting a negative compounding effect to the machines individually, and other single means for imparting a positive compounding effect to the machines jointly.

4. In a system of regenerative control, the combination with a plurality of momentum-driven dynamo-electric machines, of an exciter system embodying means for imparting a predetermined compounding effect to the machines individually and for imparting an opposing compounding effect to the machines jointly. 85 90

5. In a system of regenerative control, the combination with a plurality of momentum-driven dynamo-electric machines, of an exciter system embodying means for imparting a predetermined compounding effect of one type to the machines individually and for imparting a compounding effect of the opposite type and of a different degree to the 100 machines jointly. 95

6. In a system of regenerative control, the combination with a plurality of momentum-driven dynamo-electric machines, of an exciter system embodying means for imparting a negative compounding effect to the machines individually and a lesser positive compounding effect to the machines jointly. 105

7. In a system of regenerative control, the combination with a plurality of momentum-driven dynamo-electric machines, of means for effecting joint operation of said machines in accordance with a relatively "flat" speed-torque curve, means for preventing sudden variations of regenerated current, 110 and relay means for normally maintaining the regenerated current within predetermined limits. 115

8. In a system of regenerative control, the combination with a plurality of momentum-driven dynamo-electric machines, of exciter means for effecting joint operation of said machines in accordance with a relatively "flat" speed-torque curve, resistor means for preventing sudden variations of regenerated current, a motor-type relay having its armature and field winding so energized as to maintain regenerative action within prede- 120 125

terminated limits, and means for manually adjusting the armature current of said relay.

9. In a system of regenerative control, the combination with a momentum-driven dy-

5 namo-electric machine, of a plurality of relay devices for normally maintaining the regenerated current within predetermined limits, and means dependent upon an interruption of the regenerative current for
10 maintaining the generated voltage within predetermined limits.

10. In a system of regenerative control, the combination with a momentum-driven dynamo-electric machine, of a plurality of
15 motor-type relay devices having their armatures and field windings so energized as to normally maintain the regenerated current within predetermined limits, and a plurality of independent relays energized
20 upon an interruption of the regenerative circuit for maintaining the generated voltage within predetermined limits until the regenerative circuit is resumed.

11. In a system of regenerative control,
25 the combination with a supply circuit and a momentum-driven dynamo-electric machine, of a plurality of motor-type relay devices having their armatures and field windings so energized as to normally maintain the
30 regenerated current within predetermined limits, a relay for rendering said motor-type relay devices inoperative upon an interruption of supply-circuit voltage, and a plu-

rality of solenoid-type relays for thereupon maintaining the generated voltage within 35 predetermined limits until the resumption of supply-circuit voltage.

12. In a system of regenerative control, the combination with a momentum-driven dynamo-electric machine, of means for normally maintaining the regenerated current within predetermined limits, and means dependent upon an interruption of the regenerative current for maintaining the generated voltage within predetermined limits. 40 45

13. In a system of regenerative control, the combination with a supply circuit and a momentum-driven dynamo-electric machine, of a controller for governing the excitation of the machine, a plurality of torque-relay 50 means dependent upon the regenerated current for correctively actuating said controller to maintain such current within predetermined limits, means for rendering said torque-relay means inoperative upon an interruption of supply-circuit voltage, and a plurality of relay devices dependent upon the generated machine voltage for thereupon correctively actuating said controller to maintain such voltage within predetermined limits. 55 60

In testimony whereof, I have hereunto subscribed my name this 22nd day of March 1917.

RUDOLF E. HELLMUND.
